UNITED STATES PATENT OFFICE.

CHARLES LIPPINCOTT AND JAMES PATTERSON, OF PHILADELPHIA, PA.

DESIGN FOR SODA-WATER APPARATUS.

Specification forming part of Design No. **6,511**, dated April 1, 1873; application filed March 19, 1873.

To all whom it may concern:

Be it known that we, CHARLES LIPPINCOTT and JAMES PATTERSON, both of the city and county of Philadelphia and State of Pennsylvania, have invented a Design for Soda-Water Apparatus, of which the following is a specification:

The perspective view of the accompanying drawing clearly represents our design for soda-water apparatus, the general form of which is that of a cottage, having four sides, surmounted by double-inclined over-hanging roofs, *a*, adjoining each other, as shown, and converging toward a central square tower, *b*, on which is a glass-curved fountain, *d*.

The apparatus has the usual draft-tubes

and sirup-faucets, and is elaborately ornamented throughout, in a manner too clearly shown in the drawing to need description.

We claim—

1. The design for the general cottage-like outline of the apparatus, irrespective of the ornamentation.

2. The design for the complete apparatus, ornamented as shown in the drawing.

In testimony whereof we have signed our names to this specification in the presence of two subscribing witnesses.

CHAS. LIPPINCOTT.

Witnesses: JAMES PATTERSON.

W.M. A. STEEL,

HUBERT HOWSON.
